UNITED STATES PATENT OFFICE.

JOHN F. MEIGS AND SIGARD A. S. HAMMAR, OF SOUTH BETHLEHEM, PENNSYLVANIA, ASSIGNORS TO BETHLEHEM STEEL COMPANY, OF SOUTH BETHLEHEM, PENNSYLVANIA, A CORPORATION OF PENNSYLVANIA.

SHIELD-MOUNT FOR GUNS.

SPECIFICATION forming part of Letters Patent No. 746,725, dated December 15, 1903.

Application filed November 26, 1902. Serial No. 132,942. (No model.)

To all whom it may concern:

Be it known that we, JOHN F. MEIGS, a citizen of the United States, and SIGARD A. S. HAMMAR, a subject of the King of Sweden and Norway, both residing at South Bethlehem, in the county of Northampton and State of Pennsylvania, have invented certain new and useful Improvements in Shield-Mounts for Guns, of which the following is a specification.

Our invention relates to means for protecting gunners in connection with gun-mounts; and it consists in the construction of the shield and its support on the gun-mount, as fully set forth hereinafter, and illustrated in the accompanying drawings, in which—

Figure 1 is an elevation of a gun-mount and shield embodying our invention. Fig. 2 is a perspective view of the shield; Fig. 3, a plan showing the top carriage and brackets in part section.

The pedestal A supports the top carriage B, consisting mainly of the yoke 3, having a pivot 1 turning in the pedestal, and a cradle C, with trunnions 8, having bearings in the yoke-piece, said cradle supporting the gun D.

The shield M consists of a metallic plate bent on a line extending approximately transversely through the gun to make the section 30 of the shield above the gun incline at a greater angle than that below to deflect to as great an extent as possible projectiles striking this part of the shield. The shield has an opening for the passage of the barrel of the gun, 35 which can slide in the cradle. The top carriage supports the shield through the medium of two brackets N N, each of which is connected at one end to the lower and at the other end to the upper section of the shield, 40 while the central or intermediate portion is bolted to the top carriage or yoke. As shown, the lower portion of the bracket is bent upon itself to form a loop, to the free end of which the shield is attached, while the upper end of 45 the bracket extends above the carriage or yoke and is rearwardly inclined to conform with the angle of the upper shield-section. The forward faces of the top carriage or yoke 3 are formed to constitute bearing-faces for 50 the central parts of the brackets N N, each being bolted to one of said faces by bolts e. e. As thus attached the shield is rigidly sup-

ported to move with the gun about its pivot, so that the opening in the shield need be only as wide as the barrel of the gun. It will be seen that by bolting the brackets to the front faces of the top carriage or yoke much more extended bearings can be had than could otherwise be obtained, thereby securing a firmer support.

To avoid the injuries resulting from the detachment of bolt-heads by the action of projectiles, we make use of bolts or rivets f with flaring heads and countersink the openings in the shield to receive said heads, the ends of the bolts therefore being flush with the outer face of the shield.

Without limiting ourselves to the construction shown, we claim—

1. The combination with the yoke of a gun-mount, of a shield through which the gun extends, and brackets supporting the shield at their opposite ends and centrally connected to the forward faces of the yoke, substantially as set forth.

2. The combination with the yoke of a gun-mount, of a shield through which the gun extends, and brackets supporting the shield at their opposite ends and centrally connected to the forward faces of the yoke, the lower ends of the brackets being loop-shaped, substantially as set forth.

3. The combination with the yoke of a gun-mount, of a shield through which the gun extends, and brackets each connected at its opposite ends to the shield at points above and below the top of the yoke and at intermediate points to the yoke, substantially as set forth.

4. The combination with a gun-mount, of a shield extending above and below the gun at different angles, and brackets each centrally connected to the gun-mount and at their ends to the shield above and below the line on which it is bent, substantially as set forth.

In testimony whereof we have signed our names to this specification in the presence of two subscribing witnesses.

JOHN F. MEIGS.

SIGARD A. S. HAMMAR.
